(57) **CLAIM**

The ornamental design for a space heater with remote control, as shown and described.

DESCRIPTION

FIG. 1 is a front elevational view of the space heater with remote control of the present invention;

FIG. 2 is a rear elevational view of the space heater with remote control of FIG. 1;

FIG. 3 is a left side elevational view of the space heater with remote control of FIG. 1;

FIG. 4 is a right side elevational view of the space heater with remote control of FIG. 1, the left view of the receiver being a mirror image thereof;

FIG. 5 is a top plan view of the space heater with remote control of FIG. 1; and,

FIG. 6 is a bottom plan view of the space heater with remote control of FIG. 1.

The cord is shown broken away to indicate indeterminate length.
